(57) CLAIM

The ornamental design for the clip, as shown and described.

DESCRIPTION

FIG. 1 is a perspective view of the clip showing my new design in use condition;

FIG. 2 is a rear view thereof;

FIG. 3 is a front view thereof;

FIG. 4 is a left side view thereof;

FIG. 5 is a right side view thereof; and,

FIG. 6 is a top plan view thereof.

Wherein the dotted lines herein illustrate environment and use and do not form any part of the claimed design.
